CLAIM

The ornamental design for an enclosable mobile blood collection apparatus, as shown and described.

DESCRIPTION

FIG. 1 is a perspective view of the enclosable mobile blood collection apparatus and cover therefor;

FIG. 2 is a top view of the blood collection apparatus without the cover;

FIG. 3 is a front view thereof;

FIG. 4 is a right-hand side view thereof, the left-hand side view being depicted in FIG. 1;

FIG. 5 is a bottom view of the assembled enclosure housing the blood collection apparatus.
